H. E. MILLER,

AUTO CURTAIN.

APPLICATION FILED APR. 22, 1914.

1,161,149.

Patented Nov. 23, 1915.

UNITED STATES PATENT OFFICE.

HARRY E. MILLER, OF WAPITI, WYOMING.

AUTO-CURTAIN.

1,161,149

Specification of Letters Patent. Patented Nov. 23, 1915.

Application filed April 22, 1914. Serial No. 833,697.

To all whom it may concern:

Be it known that I, HARRY E. MILLER, a citizen of the United States, residing at Wapiti, in the county of Park, State of Wyoming, have invented certain new and useful Improvements in Auto-Curtains; and I do hereby declare the following to be a full, clear, and exact description of the invention, such as will enable others skilled in the art to which it appertains to make and use the same.

This invention relates to vehicles and has special reference to that type of vehicle which is open on the sides and which employs curtains to close in the sides, for instance such vehicles as automobile touring cars. Moreover the invention relates to vehicle having side doors.

The principal object of the invention is to provide an improved curtain arrangement for vehicles of this description.

A second object is to provide a certain arrangement of rigid panes of transparent material, such as glass, in the curtains and which will permit the storage of such curtains out of the way when not in use.

With the above and other objects in view the invention consists in general of certain novel details of construction and combination of parts hereinafter fully described, illustrated in the accompanying drawings, and specifically claimed.

In the accompanying drawings, like characters of reference indicate like parts in the several views, and:—Figure 1 is a side elevation of a portion of an automobile body showing the door and the curtains in use. Fig. 2 is a similar view showing the door as it appears when the curtain is stored therein. Fig. 3 is a section on the line 3—3 of Fig. 2. Fig. 4 is a section on the line 4—4 of Fig. 2. Fig. 5 is an enlarged detail view on the line 5—5 of Fig. 1. Fig. 6 is an enlarged detail view showing a portion of the center and one side curtain with the roller curtain attached thereto.

In carrying out the objects of this invention the usual automobile body 10 is provided with a hinged door 11. This door consists of inside and outside panels connected by suitable edge pieces 12 so as to form a hollow body. Within the body 12 and extending longitudinally of the door is a spring roller 13 to which is attached one end of a web 14 of light duck or other like material. To the upper edge of this web is

sewed the main curtain 15 the web being sufficiently long so that when the main curtain is in the position shown in Fig. 1 the web will just come to the edge of the door. To the upper edge of the main curtain is secured a closure strip 16 which is so arranged that when the web 14 is wound up on the roller 13 the strip 16 will act as a closure for the upper or normally open edge of the door 11. The curtain 15 is surrounded by a suitable reinforcing band 17 and attached to this reinforcing band at each side of the curtain is a piece of webbing 18 which constitutes a species of hinge. To this hinge is sewed the side curtain 19, it being obvious that either one or two of these curtains may be used depending on the construction of the machine. These curtains, like the main curtain are surrounded by a reinforcing strip 20 so that the bending of one curtain on the other occurs at the hinge strip 18. Each of the curtains is provided with a central opening wherein is located a pane of glass or other transparent material as indicated at 21, this material being held in position in a suitable frame 22 fixed to the curtain body by sewing, riveting or the like. Through the edges of the various curtains are made suitable perforations to receive gromets 23 which are arranged to engage over buttons 24 on the body of the automobile and on the automobile top.

The curtain under normal circumstances remains within the door. When it is desired to use this curtain the strip 16 is grasped and the curtain, together with the side curtains pulled out. The main curtain then has its gromets engaged over appropriate buttons and the side curtains are unfolded and the gromets on these curtains likewise engaged over suitable buttons. It is to be observed that by reason of this arrangement the curtains themselves are never rolled or doubled but are simply folded one on the other so that the panes of glass or other transparent material are not engaged by the roller and consequently cannot be broken since the proportions of the web and the curtain height are such that no part of the curtain is rolled on the roller when the latter is stored in the door. There has thus been provided a simple and efficient device of the kind described and of the character specified.

It will be obvious that many minor changes may be made in the form and con-

struction of this invention without departing from the material principles thereof. It is not therefore desired to confine the invention to the exact form herein shown and described, but it is wished to include all such as properly come within the scope claimed.

Having thus described the invention, what is claimed as new, is:—

- 10 1. The combination with a vehicle door having a hollow body and an open top edge; of a spring roller mounted within said body adjacent the bottom thereof, a strip of flexible material having one end secured to said roller and adapted to be wound thereon, a curtain having its bottom edge attached to the free end of said strip, and a closure strip attached to the upper edge of the curtain and seating on the upper edge of the door when the curtain is retracted.
- 15 2. The combination with a vehicle door having a hollow body and an open top edge; of a spring roller mounted within said body adjacent the bottom thereof, a strip of flexible material having one end secured to said
- 20
- 25

roller and adapted to be wound thereon, a curtain having its bottom edge attached to the free end of said strip, a side curtain flexibly connected to the side of the first curtain to fold thereon for retraction, and means to limit retraction of said curtains.

3. The combination with a vehicle door having a hollow body and an open top edge; of a spring roller mounted within said body adjacent the bottom thereof, a strip of flexible material having one end secured to said roller and adapted to be wound thereon, a curtain having its bottom edge attached to the free end of said strip, a side curtain flexibly connected to the side of the first curtain to fold thereon for retraction, and a closure strip attached to the upper edge of the first curtain and seating on the upper edge of the door when the curtains are retracted.

In testimony whereof, I affix my signature, in the presence of two witnesses.

HARRY E. MILLER.
